(57) **CLAIM**

The ornamental design for a door for a refrigerator, as shown and described.

DESCRIPTION

FIG. 1 is a front isometric view, showing the ornamental design of a door for a refrigerator.

FIG. 2 is a top view of the door shown in FIG. 1.

FIG. 3 is a right side view of the door shown in FIG. 1; and, FIG. 4 is a front view of the door shown in FIG. 1.

The broken lines showing elements in the drawings are for illustration purposes only and form no part of the claimed design.
